FILTER PLATE REMOVING TOOL FOR PIPES

Filed Oct. 28, 1922

FIG. 1.

FIG. 2.

FIG. 3.

FIG. 4.

FIG. 5.

FIG. 7.

Inventor
KALMAN VERESS

By his Attorney Julian J. Wittal

Patented Dec. 6, 1927.

1,651,790

UNITED STATES PATENT OFFICE.

KALMAN VERESS, OF NEW YORK, N. Y.

FILTER-PLATE-REMOVING TOOL FOR PIPES.

Application filed October 28, 1922. Serial No. 597,496.

This invention relates to pipes for smoking tobacco and has for its main object to provide means in the devices of the mentioned character whereby the smoke of the 5 tobacco will be cleaned, cooled and relieved of most of its nicotine and other harmful and disagreeable substances, juices and odors before reaching the mouth of the smoker.

10 Another object of this invention is to provide devices of the character described which will help in the even distribution of the tobacco in said pipes and in its economical consumption while said devices are of 15 such a nature that they are inexpensive in manufacture and easily applied or removed.

For a full description of the invention and the merits thereof and also to acquire a knowledge of the details of construction of 20 the same for effecting the various results mentioned hereinbefore, reference is to be had to the following description and accompanying drawings.

While the essential and characteristic features of the invention are susceptible of modification, still the preferred embodiment of the invention is illustrated in the accompanying drawings, in which:—

Fig. 1 is a longitudinal sectional view 30 taken through the center line of a pipe, showing the application of the invention;

Fig. 2 is a similar view of the same, indicating the manner of applying the device;

Fig. 3 is a similar sectional view indicating the tamping of the tobacco;

Fig. 4 is a perspective view of the tamping rod employed;

Fig. 5 is a similar view showing a different form of construction of tamping rod;

40 Fig. 6 is a perspective view of the perforate separator;

Fig. 7 is a similar perspective view of the separator lining, and

Fig. 8 is a plan view of a modification of 45 my circular straining plate.

In the several views, an ordinary form of pipe is disclosed, the same consisting of a body 10, having a bowl or chamber 11, and stem 12, with which is engaged the mouth piece or nib 13, passages 14 and 15 passing through the stem and nib respectively, the whole representing a conventional form of pipe.

The invention consists of a circular plate 55 18, having a central opening 23 and a plurality of relatively small perforations 19

formed therethrough, there being a plurality of slits or notches 20 in its periphery, forming in effect radial leaves 21, rendering the plate extremely resilient and easily inserted in the bowl 11 of the pipe. 60

Also formed with certain of the leaves 21 are one or more extensions coiled into rolls 22, the same being co-incident with the periphery of the plate leaves and containing 65 openings by means of which the plate may be raised.

A disk 24 of felt or similar thick fabric is adapted to be engaged with the lower side of the plate 18, being held thereto by 70 any suitable adhesive and also by the edges of the metal as forced down in perforating the plate.

In order to conveniently apply the separator, a rod 25 is provided with a hook 26 75 at one end, the same being engageable within the openings in the coiled projections 22, by means of which the plate may be raised, the opposite end of the rod being coiled into a circular loop 27, from which depends a 80 central element 28, engageable through the central opening 23, with the hole 29, formed in the felt disk 24, the pin or projection 28 acting as a guiding means whereby the plate 18 may be pressed level and uniformly within the bowl of the pipe. 85

In the adaptation shown in Figure 5, in place of the coiled loop 27, a rigid circular plate 30 is attached to the rod 25 the same extending therethrough and acting in a 90 manner similar to the pin 28.

It will also be obvious that the elements 27 or 30 may be used in tightly tamping the tobacco, as indicated in Fig. 3, and it will be understood that in all cases the peripheral edge of the plate leaves 21 tightly impinges against the interior of the chamber or bowl 11 so as to form an open space or chamber 16 at the bottom of the bowl, directly communicating through the passages 14 and 15, with the smoker's mouth, and that by reason of the perforations and felt disk, the smoke is drawn in a relatively cool and pure condition, all deleterious substances being removed by the filtering effect 105 obtained.

Fig. 8 shows a simplified embodiment of my straining plate 18, the hollow extensions 22 having been done away with and the whole device consisting of circular plate 110 31 with radial incisions 32 and one or more perforations 33 in the center portion of the

same, said perforations being used both for straining the smoke and for applying any suitable means for removing the plate 31 from the pipe.

5 Having thus described my invention, what I claim as new, and desire to secure by Letters Patent, is:—

A tool for manipulating and removing a filter plate from a tobacco pipe bowl, said 10 tool being formed of a comparatively heavy piece of wire having a shank portion and

provided at one end with a hook for engaging said plate, and at its other end with a loop wound transversally of the shank, said loop having a depending central pin, 15 as and for the purpose described and specified.

Signed at New York in the county of New York and State of New York this 16th day of October A. D. 1922.

KALMAN VERESS.
